Primary Examiner — Jae Liang*Assistant Examiner* — Bryan C Gusman(74) Attorney, Agent, or Firm — MUNCY, GEISSLER, OLDS & LOWE, P.C.(57) CLAIM

The ornamental design for a desk as shown and described.

DESCRIPTION

FIG. 1 is a top, front perspective view of a desk showing my new design;

FIG. 2 is a top, rear perspective view thereof;

FIG. 3 is a bottom, front perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof; and,

FIG. 10 is a portion of the perspective view of FIG. 1 enlarged for magnification purposes.

The dash-dash broken lines depict portions of the article and form no part of the claim. The dash-dot broken lines depict the cut line of the enlarged views and form no part of the claim.

1 Claim, 10 Drawing Sheets(56)
